UNITED STATES PATENT OFFICE.

BERT ASHBY, OF EL PASO, TEXAS.

PACKET-HOLDER.

1,328,869.

Specification of Letters Patent. Patented Jan. 27, 1920.

Application filed June 21, 1919. Serial No. 305,738.

To all whom it may concern:

Be it known that I, BERT ASHBY, a citizen of the United States, residing at El Paso, in the county of El Paso and State of Texas, 5 have invented certain new and useful Improvements in Packet-Holders, of which the following is a specification.

This invention relates to package ties, and more especially to those employing a cord 10 and a clasp plate; and the object of the same is to produce a packet holder intended more particularly for wrapping and tying a bundle of mail matter such as a bunch of letters which have been sorted and are 15 all addressed and to be sent to the same city or town. The Post Office Department desires an article of this class which, in addition to simplicity of structure and consequent inexpensiveness, shall be durable 20 and particularly capable of quick application to a package or packet, which it must hold with a grip not likely to become loosened in the rough usage to which mail matter is subjected in transport.

25 It is the aim of the present invention to produce an article for filling these requirements, to which end the first feature of the invention is its extreme simplicity as it consists merely of a plate of sheet metal which 30 can be formed at a single stroke of the die, and a cord attached to one end of the plate.

Coincidently and necessarily it is another 35 object of the invention to produce an article which is cheap, easy to handle, and durable. details are set forth below, and reference is made to the drawings wherein:

Figure 1 is a plan view of a package or 40 packet tied by the use of this improved device.

Fig. 2 is an enlarged central longitudinal section through the plate.

Stamped by a die or otherwise formed 45 from a sheet of appropriate and slightly resilient metal is a plate whose body is herein numbered 1, its front and rear ends and corners being rounded as at 2, and its front end which will be called the toe being pierced with an eye 3 into which a cord 4 is passed and tied or knotted at one end as 50 at 5, the cord being long enough to reach from the toe end of the plate once around the packet 6 lengthwise and then at least once around the same packet crosswise and its free extremity being indicated at 7. 55 Many devices of this kind have such a plate and such a cord, and the details of the pres-

ent invention lie in the specific shape of that part of the plate which is to engage the cord where it makes the first bend 8 and again where it is passed across the plate 60 near its free end.

Said plate is preferably made by stamping it from sheet metal, and in the act of stamping it it is cut with two parallel slits 10 and 11 connected at their forward ends 65 by a cross slit 12 and thus leaving between them a member or tongue 13 which is integral with the remainder of the plate at the rear end or heel of the latter and at the point 14 which is the shank of the tongue. 70 The latter in its final formation extends from said shank obliquely downward and forward as at 15, is bent at an acute angle and carried thence upward in a shoulder 16, is bent at an angle and thence carried 75 forward at 17 in a stretch which lies normally just below the plane of the plate as seen in Fig. 2, and forward of this stretch the tongue is humped downwardly a little as at 18 leaving its tip 19 standing in the 80 plane of the plate but considerably withdrawn from the front end of the opening produced by the cross slit 12 due to the formation of these several bends in the tongue. It is preferred that no part of the tongue 85 shall rise normally above the plane of the plate, and therefore at least one side of this device is flat and extraneous objects will not catch thereon when the article lies on a bench or table or when it is kept in a box 90 as usual. The terms "upward" and "downward" have been used in connection with the parts of the tongue as describing them 95 with reference to the entire article when standing in its normal or working position, because the active face of the plate is opposite to that beyond which the shoulder 16 extends.

In tying a packet 6 with this article, the plate is laid on the packet about as seen in Fig. 1, and the cord led from the toe end thereof over one end of the packet at *a*, across the back of the packet and over the other end at *b*, then the tip 19 of the tongue is raised and the cord passed thereunder and bent at the point 8, and the loop around the packet endwise drawn quite tight. This forces the cord well back against the face of the shoulder 16, and raises the stretch 17 sufficiently high to allow the transverse cord to pass beneath it and across the plate. 105 Thence the cord is led around one edge of 110

the packet as at *c* and across the back of the same and around the other edge as at *d*, and its free end is again passed under the tip 19 and brought to rest beneath the stretch 17, 5 and the spring of the tongue which has a normal downward tendency will bear both stretches of cord onto the side bars of the plate and prevent it from slipping. The tip of the tongue can be raised by inserting the 10 finger nail beneath it, or it can be caused to rise by pressing the entire plate downward onto the packet so that the latter forces upward the angle between the stretch 15 and the shoulder 16. As soon as either stretch 15 of cord is passed under the tip and moved toward the rear end of the plate, its movement causes it to travel beneath the hump 18 which necessarily raises the tongue. Finally the first stretch of cord will come to 20 rest against the shoulder 15 and the second stretch of cord against the first stretch, and the downward tendency of the tongue will cause the stretch 17 to bear both stretches of cord onto the side bars of the body. Thus 25 all the various parts or stretches of the tongue have their appropriate functions, and in the final condition of parts that stretch or loop of the cord which embraces the packet lengthwise lies in contact with that 30 which embraces it transversely so that not only does the tongue grip both loops, but it holds the stretches of both loops in contact with each other. While the preferred and usual manner of tying the packet has been 35 described, it is quite possible to carry the cord around it transversely first and endwise last, and it is also possible to carry either or both the loops a second time around the packet. The grip of the stretch 17 of the 40 tongue upon the cord is such that in some cases it may be sufficient to form the cord into but a single loop passing around the packet only once; or in other words, it is not neces-

sary to the successful operation of the device that a plurality of stretches of cord 45 shall underlie the raised portion 17 of the tongue. Therefore, the widest latitude is reserved as to the uses of this device, and its materials and proportions of parts may be left to the manufacturer. 50

Having thus described the invention, what is claimed as new is:

1. A package tie including a body, and a tongue connected to the body and having cord engaging means normally disposed below the plane of the body and adapted to be temporarily positioned above the plane of the body to engage a cord. 55

2. A package tie including a body, and a tongue connected to the body and having 60 cord engaging means, the rear end portion of said tongue being extended downwardly for normally disposing said cord engaging means below the upper side of the body.

3. A package tie including a body, and a 65 tongue connected to the body and having cord engaging means, the rear end portion of said tongue being extended downwardly for normally disposing said cord engaging means below the upper side of the body, the 70 forward end portion of said tongue being normally disposed in the plane of the body for presenting a flat upper surface to the body.

4. A package tie including a body having 75 longitudinal and transverse incisions forming a tongue, said tongue having its intermediate portion provided with a pair of shoulders forming a cord engaging member, the rear end portion of said tongue 80 being extended downwardly for normally disposing said cord engaging member below the upper side of the body.

In testimony whereof I affix my signature.

BERT ASHBY.
